INTERNAL-COMBUSTION ENGINE

Wilhelm B. Bronander, Montclair, N. J.

Application July 3, 1945, Serial No. 603,070

7 Claims. (Cl. 123—41.69)

1

This invention relates to internal-combustion engines and particularly to the construction and cooling of cylinder heads.

At the present time, internal-combustion engines and, more especially, aircraft engines, are operated under very high compression and at exceedingly high speeds and develop enormous amounts of heat which must be dissipated. This is particularly true with high octane fuels such as are being used in bombers and fighter planes where speed is most essential.

Under these conditions it has become very difficult to provide adequate cooling facilities for the cylinders and cylinder heads and, more especially, for the portions of the heads around the exhaust ports which become so hot that the lubricant for the valve mechanism burns out, valves freeze, and the cylinder head itself is punctured and destroyed.

This invention has for its salient object to overcome the difficulties above set forth and to provide a cylinder head and heat dissipating and cooling means so constructed and arranged that the head will be adequately cooled.

Another object of the invention is to provide a simple and practical method of grooving a cylinder head to receive cooling fins.

Further objects of the invention will appear from the following specification taken in connection with the drawings which form a part of this application, and in which

Fig. 1 is a vertical sectional elevation, partly broken away, showing the upper portion of an engine cylinder and a cylinder head mounted thereon and constructed in accordance with the invention;

Fig. 2 is a vertical sectional elevation taken substantially on line 2—2 of Fig. 1, looking in the direction of the arrows;

Fig. 3 is a vertical sectional elevation of the upper portion of one construction of the cylinder and the intake and exhaust ports embodying the invention, before the valve housings are mounted on the head;

Fig. 4 is a plan view, partly in section, taken substantially on line 4—4 of Fig. 3, looking in the direction of the arrows, the intake port flange being removed;

Fig. 5 is a vertical sectional elevation similar to Fig. 3 but showing the exhaust port threaded to receive a threaded flange and showing the head prior to cutting the intake port therethrough;

Fig. 6 is an enlarged sectional elevation showing fins secured thereto;

Fig. 7 is a sectional elevation similar to Fig. 6 but showing a preferred method of anchoring the fins; and

Fig. 8 is a view similar to Fig. 4 but showing the fin groove formed in a spiral about the center of the exhaust port as an axis.

2

The invention may be briefly described as consisting of a cylinder head having intake and exhaust ports and having formed or mounted thereon a plurality of cooling fins extending outwardly from the outer surface of the head and centered around the axis of the exhaust port and exhaust valve. Furthermore, the cooling fins may consist of inverted truncated cones having a common apex disposed on said exhaust port axis and, more particularly stated, disposed at the point of intersection of the axes of the intake and exhaust ports.

Further details of the invention will appear from the following description.

In the particular embodiment of the invention illustrated in the drawings there is shown the upper end 10 of a cylinder having circumferential grooves 11 in which are mounted cooling fins 12 of any desired construction, those illustrated being similar to the fins shown in my Patent No. 2,363,224.

To the upper end of the cylinder 10 there is secured in any suitable manner, a cylinder head 15 which, in the form of the invention shown, is threaded to the upper end of the cylinder. The cylinder head has an intake port 16 and an exhaust port 17, these ports being so disposed that their axes X and Y intersect at a point Z which is disposed on the vertical axis of the cylinder 10.

In the form of the invention shown in Figs. 1, 2 and 3, the cylinder head 15 has an outwardly extending, outwardly flared flange 18 which is disposed around the exhaust port 17. The intake port 16 or intake opening is threaded, as shown at 20, and a ring 21 is secured in the threaded opening and has an outwardly extending and outwardly flared flange 22. If desired, the flanges 18 and 22 may be welded to the head.

The big problem in connection with the cooling of cylinder heads is the provision of adequate cooling means for the exhaust port and exhaust valve housing mounted thereon. In the present invention, before the exhaust valve housing 25 and the intake valve housing 26 and the ring 21 and flange 22 are secured in position on the cylinder head 15, the outer surface of the head is provided with a plurality of concentrically arranged grooves 30. These grooves are preferably formed concentrically about the axis Y of the exhaust port 17 and, furthermore, the grooves are formed in such a manner as to lie within surfaces of revolution formed by revolving radii in concentric circles about a point Z on the axis Y of the exhaust port. In this particular embodiment of the invention illustrated, this point Z, as above explained, is located at the point of intersection of the axes X and Y of the intake and exhaust ports.

After the grooves 30 have been formed in the cylinder head in the manner above described by relative rotation of the cylinder head and cut-

ting tool about the axis Y, cooling fin strips 31 are secured in the grooves 30 in any desired manner and are firmly anchored therein. The fin strips consist of inverted truncated cones having a common apex positioned at the point Z and the fins, therefore, are radially disposed with reference to the point Z and flare outwardly, being disposed closer together at the surface of the cylinder head and diverging therefrom.

After the grooves have been formed as above described and the fins have been secured therein, the intake and exhaust valve housings 25 and 26 are secured to the cylinder head. In the form of the invention shown, the intake valve seat 35 and the exhaust valve seat 36 are formed at the inner ends of sleeves 37 and 38 which are provided with external threads 39 and 40. The exhaust valve housing 25 has a portion 41 which is threaded on the threaded portion 40 of the sleeve 38 and a corresponding portion 42 on the intake valve housing 26 is threaded on the threaded portion 39 of the sleeve 37.

The valve housings 25 and 26 have laterally extending flanges 45 and 46 which extend over and engage the outer flanged ends 47 and 48 of the flanges 18 and 22.

Cooling fins 50 are formed on the exhaust valve housing 25 but these fins do not embody the invention described and claimed in this application.

From the showings in Figs. 1 and 2 particularly it will be clear that the surfaces of the fins are conically disposed or consist of inverted truncated cones which intersect at a common apex Z. Moreover, these cones, when shown in section, as in Figs. 1 and 5, are radially disposed with reference to the point Z.

In Fig. 5 the exhaust port opening 55 is threaded in a manner similar to the intake port 16 in Fig. 1. Fig. 5, however, shows the cylinder head before the intake port has been bored. The grooves 30 are preferably cut in the head before the intake port is bored and these grooves are formed, as above described, about the center of the exhaust port. After the grooves 30 are cut the intake port is formed in the head.

Figs. 6 and 7 show the fins 31 mounted in the grooves 30. They may be anchored in any desired manner and are preferably tapered in thickness, being thicker adjacent the head. If desired, the grooves may be formed in a spiral with the center of the spiral at the center of the exhaust port, as illustrated at 30' in Fig. 8. In Fig. 8 the cylinder head is grooved in a spiral 30' about the axis of exhaust port 17 before the intake port 16 is formed. Portions of the spiral extend beyond the head and are shown in dotted lines.

From the foregoing specification it will be evident that a simple and practical method has been provided for grooving cylinder heads in such a manner that the cooling fins can be mounted on the head concentrically around the axis of the exhaust port, which portion of the cylinder head requires the greatest cooling or dissipation of heat. Furthermore, by providing fins which flare outwardly from the cylinder head, a maximum cooling effect is obtained since the cooling air has ready access to the spaces between the fins.

Although one specific embodiment of the invention has been particularly shown and described it will be understood that the invention is capable of modification and that changes in the construction and in the arrangement of the various cooperating parts may be made without

departing from the spirit or scope of the invention, as expressed in the following claims.

What I claim is:

1. A cylinder head having an exhaust port and an exhaust valve seat therein, and cooling fins mounted on said head and disposed substantially concentrically with relation to a common axis on the axis of said exhaust valve port and seat and diverging from the outer surface of the head outwardly.

2. A cylinder head having an exhaust port and an exhaust valve seat therein, said head having substantially circular grooves in its outer surface having a common center on the axis of said exhaust port and valve seat, and cooling fins mounted in said grooves.

3. A cylinder head having an exhaust port and an exhaust valve seat therein, said head having grooves in its outer surface centered substantially on the axis of said exhaust port and valve seat, and cooling fins mounted in said grooves, the outer portions of said fins being spaced apart a greater distance than the portions secured in the grooves.

4. A cylinder head having an exhaust port and an exhaust valve seat therein, and cooling fins carried by said head and disposed substantially concentrically with relation to the axis of said exhaust valve port and seat and disposed within surfaces of revolution described by radii moved in circles about a center disposed on said axis.

5. A cylinder head having an exhaust port and an exhaust valve seat therein, and cooling fins consisting of inverted truncated cones having a common apex disposed on the axis of said exhaust valve and seat.

6. A cylinder head having an intake port and an exhaust port, and a plurality of cooling fins carried by said head and consisting of inverted truncated cones formed about the axis of the exhaust port axis as a center and having a common apex disposed at the point of intersection of the axes of the intake and exhaust ports.

7. A cylinder head having an exhaust port, and a cooling fin groove disposed spirally about the axis of the exhaust port as a center and a cooling fin mounted in said groove and having its outer portions spaced apart a greater distance than the portions in the groove.

WILHELM B. BRONANDER.
